UNITED STATES PATENT OFFICE.

WILLIAM A. BUTCHART, OF DENVER, COLORADO.

LIQUID-FEEDING DEVICE.

1,256,516.

Specification of Letters Patent. Patented Feb. 19, 1918.

Application filed June 25, 1917. Serial No. 176,928.

To all whom it may concern:

Be it known that I, WILLIAM A. BUTCHART, a citizen of the United States, residing at Denver, Colorado, have invented a certain new and useful Improvement in Liquid-Feeding Devices, of which the following is a full, clear, and exact description, such as will enable others skilled in the art to which it appertains to make and use

10 the same.

This invention relates to liquid feeding devices of the type that comprise a rotatable element partially submerged in a body of liquid, and a scraper arranged in an inclined position in proximity to said rotatable element, so that it will scrape off or remove the liquid that adheres to said element and feed said liquid to the apparatus or mechanism with which the device is used.

20 The main object of my invention is to provide a liquid feeding device of the general type referred to, in which the rotatable element consists of a substantially disk-shaped member partially submerged in the liquid and the feeding means consists of one or more scrapers arranged so that they will remove the material that adheres to one or both of the vertical side faces of said member, thereby making it possible to feed liquid to a number of points or to a number of separate and distinct machines or devices by means of a single rotatable element of comparatively small size.

Another object is to provide a liquid feeding device of the general type referred to that is of simple design, of rugged construction and easy to control or regulate.

The figure of the drawings is a perspective view, illustrating a liquid feeding device constructed in accordance with my invention.

Referring to the drawing, which illustrates one form of my invention, A designates a receptacle or container that holds liquid which it is desired to supply in relatively small quantities to a machine or apparatus (not shown). B designates a rotatable element that dips into the liquid in the container A and C designates a scraping device that removes or scrapes off the liquid that adheres to the element B and feeds said liquid to the machine or apparatus with which the device is used. The rotatable element B consists of a disk-shaped member arranged vertically in the container A so that the lower portion of same will be sub-

merged in the liquid in said container. The scraper C consists of a trough-shaped device arranged in an inclined position and so disposed with relation to the rotatable element B that the upper end or inner end *x* of the scraper will extend parallel to the vertical side face *a* of the disk B, and thus scrape off the liquid that adheres to the side face *a* of said disk. By constructing the device in this manner I am able to use the other vertical side face of the disk B to convey the liquid in the container A to a second scraping device C' arranged on the opposite side of the disk B. The scraper C is arranged at substantially right angles to the disk B, so that the inner end of said scraper will be presented to the vertical side face of the disk B with which it coöperates, but the scraper C' is arranged substantially parallel to the disk B, so that one of the side edges at the upper end of same will remove the liquid that adheres to the other vertical side face of said disk, the liquid that is removed from the disk by the scrapers C and C' flowing down said scrapers and being discharged from the lower ends of same. The rotatable element B can be mounted in various ways without departing from the spirit of my invention, but I prefer to secure said element to a horizontally-disposed shaft 1 that is journaled in bearings 2 on the liquid container A. Any suitable means can be used for driving the element B, but I prefer to form teeth 3 on the peripheral edge of the disk B, thus converting it into a gear, and drive said gear by means of a pinion 4 on a drive shaft 5 provided with a pulley 6 that coöperates with a driving belt (not shown). By constructing the device in this manner I am able to use the ordinary line shafting of a mill or factory for driving the disk B at a sufficiently slow speed to insure the delivery of relatively small quantities of liquid from the discharge ends of the scrapers C and C', a thing that is rather difficult to accomplish when the shaft to which the rotatable element is connected is driven directly by a belt passing around a pulley on said shaft.

105 In order that the quantity of liquid delivered by the scrapers C and C' may be accurately controlled, I have provided means for adjusting said scrapers relatively to the rotatable element B, so as to vary the effective scraping areas of the devices C and C' that are presented to the element B.

Any suitable adjusting means may be used for this purpose, but one means that I have found to be very efficient consists of an adjusting screw on the liquid container connected to the scraper with which it is used in such a manner that the effective scraping area of the scraper will be increased when said screw is turned in one direction and will be diminished when said screw is turned in the opposite direction.

In the device herein illustrated an adjusting screw 7 provided with a knurled head or finger piece 8 is mounted on the container A at substantially right angles to the scraper C, said screw being journaled in one of the end walls of said container and being provided in its inner end with a screw-threaded portion 9 that is threaded into one of the shaft bearings 2. The scraper C is provided on its underside with a block 10 through which the screw 7 passes, and washers or abutments 11 are arranged on said screw at opposite sides of said block, so as to cause the scraper C to move toward and away from the shaft 1 when the screw is turned in opposite directions, and thus cause the entire upper edge of the scraper to be presented to the vertical side face A of the disk B, or only a portion of said edge to be presented to said face. In other words, when the screw 7 is turned in one direction, the scraper C will be moved inwardly toward the shaft 1, so that the entire upper edge of same will scrape off liquid that adheres to the vertical side face of the disk B, and when said screw is turned in the opposite direction, the scraper C will be moved outwardly, so that only a portion of the upper edge of same will act on the liquid that adheres to the vertical side face A of the disk. The adjustment of the scraper C' is effected by moving said scraper in a direction parallel to the disk B, so that more or less of the upper side edge of same that acts on the disk will be presented to the vertical side face of the disk with which the scraper C' co-operates. In the device herein shown the scraper C' is held in adjusted position by means of one or more clamping bolts 12 that pass through elongated slots in the side walls of the scraper and which are tapped into a supporting block 13 on which the scraper C' rests. The complete device may either comprise one or a plurality of rotatable elements partially submerged in the liquid in the container A, and one or more scraping devices that co-operate with each rotatable element. In the form of my invention herein illustrated the device comprises two rotatable elements, the second element B' being secured to the shaft 1 to which the element B is connected and arranged so that it will co-operate with scrapers C² and C³ of similar construction to 65 the scrapers C and C', previously described.

If desired, the container A may be provided with a vertical partition 14, so as to divide the interior of same into two compartments, each of which may contain a different kind of liquid in case it is desired to use the device for feeding different kinds of liquids. By using a rotatable element consisting of a substantially vertically-disposed, disk-shaped member and arranging the scraping device in such a manner that it acts on one of the vertical side faces of said element, I am able to use a single rotatable element for supplying liquid to two feeding devices, thus practically doubling the capacity of the apparatus. Furthermore, a liquid feeding device of the construction above described is of such simple design that it can be manufactured at a low cost; it is rugged and has no parts that are apt to get out of adjustment when the device is in use; and it can be driven at a sufficiently slow speed to insure the delivery of a relatively small quantity of liquid either to a single point or to a plurality of points.

Having thus described my invention, what I claim, and desire to secure by Letters Patent, is:

1. A liquid feeding device, comprising a rotatable element of substantially disk form partially submerged in a body of liquid and arranged in a vertical position, and a device arranged to act on one of the vertical side faces of said element so as to remove liquid that adheres to same and feed said liquid to a point where it is to be used.

2. A liquid feeding device, comprising a rotatable element of substantially disk form partially submerged in a body of liquid and arranged in a vertical position, a device arranged to act on one of the vertical side faces of said element so as to remove liquid that adheres to same and feed said liquid to a point where it is to be used, and means for adjusting one of said parts relatively to the other so as to vary the effective scraping area of said device that is presented to the vertical side face of said rotatable element.

3. A liquid feeding device, comprising a rotatable element of substantially disk form arranged in a vertical position and partially submerged in a body of liquid, and a plurality of scraping devices arranged on opposite sides of said rotatable element and in such positions that they remove or scrape off the liquid that adheres to the vertical side faces of said element.

4. A liquid feeding device, comprising a rotatable element of substantially disk form arranged in a vertical position and partially submerged in a body of liquid, a plurality of scraping devices arranged on opposite sides of said rotatable element and in such positions that they remove or scrape off the liquid that adheres to the vertical side faces

of said element, and means whereby each of said scraping devices can be adjusted relatively to said rotatable element so as to vary the effective scraping area of said devices 5 and then increase or diminish the quantity of liquid that said devices remove from said element.

5. A liquid feeding device, comprising a vertically-disposed gear partially submerged 10 in a body of liquid and provided with vertical side faces to which liquid adheres when said gear is in operation, a driving pinion that meshes with said gear, and a scraping device arranged so that it will act on one of 15 the vertical side faces of said gear and remove the liquid that adheres to same.

6. A liquid feeding device, comprising a rotatable element of substantially disk form arranged in a vertical position and partially 20 submerged in a body of liquid, and an inclined scraping device arranged at substantially right angles to said element with its upper end presented to one of the vertical side faces of said element so that it will remove liquid that adheres to said side face 25 when the element is in operation.

7. A liquid feeding device, comprising a rotatable element of substantially disk form arranged in a vertical position and partially 30 submerged in a body of liquid, and an inclined scraping device arranged at one side of said element in parallel relation to same and in such a position that one of the side edges of the upper portion of said device 35 will scrape off liquid that adheres to one of the vertical side faces of said element.

8. A liquid feeding device, comprising a container provided with independent compartments that hold liquid, a substantially 40 disk-shaped, rotatable element arranged in each of said compartments in such a manner

that it dips into the liquid in same, and inclined scraping devices arranged in such a manner that they will remove liquid from 45 the vertical side faces of said rotatable elements and feed said liquid to points where the liquid is to be used.

9. A liquid feeding device, comprising a container that holds liquid, a horizontally-disposed shaft journaled in bearings on said container, a substantially disk-shaped, rotatable element on said shaft arranged in a vertical position and in such a manner that it will dip into the liquid in said container, 50 a trough-shaped scraping device arranged at substantially right angles to said element with its inner end presented to one of the vertical side faces of said element, and an adjusting screw on said container combined 55 with said scraping device in such a manner that it can be actuated to move said scraping device toward and away from the axis of rotation of said rotatable element.

10. A liquid feeding device, comprising a container that holds liquid, a horizontally-disposed shaft journaled in bearings on said container, a substantially disk-shaped, rotatable element on said shaft arranged in a vertical position and in such a manner that 60 it will dip into the liquid in said container, a trough-shaped scraping device arranged at substantially right angles to said element with its inner end presented to one of the vertical side faces of said element, an adjusting screw on said container combined 65 with said scraping device in such a manner that it can be actuated to move said scraping device toward and away from the axis of rotation of said rotatable element. 70

75

11. A liquid feeding device, comprising a container that holds liquid, a horizontally-disposed shaft journaled in bearings on said container, a substantially disk-shaped, rotatable element on said shaft arranged in a vertical position and in such a manner that 80 it will dip into the liquid in said container, teeth on the periphery of said rotatable element, and a drive shaft provided with a pinion that meshes with said teeth.

WILLIAM A. BUTCHART.
